ABSTRACT OF THE DISCLOSURE

A coin-testing device is disposed adjacent a path for coins and tests coins moving along said path, a coin-responsive element is disposed adjacent said path and is actuated by coins which have previously passed by said coin-testing device, and a control device requires a first signal from said coin-testing device and a second signal from said coin-responsive element to actuate it, and thus will not be actuated by two consecutive signals from said coin-testing device or by two consecutive signals from said coin-responsive element.

This invention relates to improvements in coin-handling devices. More particularly, this invention relates to improvements in coin-handling devices which are resistant to cheating.

It is, therefore, an object of the present invention to provide an improved coin-handling device which is resistant to cheating.

Coin-handling devices, which utilize mechanical, electro-mechanical and electronic means for testing coins, are known. When a coin is tested and accepted by such a coin-handling device, that coin will usually actuate a switch, such as a microswitch or an electronic switch; and, ordinarily, that switch will initiate the dispensing of merchandise or will apply a pulse to a credit accumulator. Some of those coin-handling devices accommodate coins of just one denomination; but other of those coin-handling devices accommodate coins of more than one denomination. In coin-handling devices that accommodate coins of just one denomination, the coins usually pass through one coin passageway and then actuate a switch as they are accepted; but, in coin-handling devices that accommodate coins of more than one denomination, the coins of different denominations are usually separated from each other and pass through different coin passageways to actuate different switches. The coin-handling device provided by the present invention makes it possible to test coins of more than one denomination in the same coin passageway, and also makes it possible to use just one switch and yet apply the proper credits, corresponding to the values of the coins of different denominations, to the credit accumulator. As a result, the present invention can provide a compact coin-handling device with a minimum of coin passageways and switches. It is, therefore, an object of the present invention to provide a coin-handling device which makes it possible to test coins of more than one denomination in the same coin passageway, and also makes it possible to use just one switch and yet apply the proper credits, corresponding to the values of the coins of different denominations, to the credit accumulator.

With some coin-handling devices, it is possible to insert an accepted coin, to which a thread or thin wire has

2

been attached, and then use that coin to obtain merchandise having a value exceeding the value of that coin or to establish credits in excess of the value of that coin. Specifically, it is possible to insert such a coin, to let that coin actuate the switch that effects the dispensing of merchandise or the applying of credits to the credit accumulator, and then to repeatedly pull and release that thread or wire so the coin will cause that switch to effect the repeated dispensing of merchandise or the repeated application of credits to the credit accumulator. With some other coin-handling devices, the switches that are supposed to be actuated by accepted coins can be actuated by blasts of compressed air or can be actuated by flexible and pliable objects which are inserted into those coin-handling devices. The present invention provides a coin-handling device which has a switch that is actuated by accepted coins; but that invention makes it impossible to use an accepted coin, to which a thread or wire has been attached, to effect the repeated dispensing of merchandise or the repeated application of credits to the credit accumulator. Also, that invention keeps that switch from being actuated by blasts of compressed air or by the insertion of flexible and pliable objects into that coin-handling device. The present invention attains these desirable results by using a coil as the switch for the coin-handling device, by interposing a coin-directing element between that coil and the unit which tests the coins, and by requiring a signal from the unit that tests the coins plus a signal from that coil before any merchandise can be dispensed or any credits can be applied to the credit accumulator. The coin-directing element is disposed adjacent a passageway for rejected coins; and it normally is in position to intercept coins. The unit which tests the coins will leave that coin-directing element in its normal coin-intercepting position if a spurious coin or a coin of the wrong denomination is inserted, and hence that coin-directing element will cause such a coin to pass to the rejected coin passageway. The unit which tests the coins will cause that coin-directing element to shift to coin-accepting position whenever an authentic coin of the proper denomination is inserted; and hence that coin will pass to the coil which acts as a switch. That coil will provide a signal which will coat with the signal, previously provided by the unit which tests the coins, to cause a credit, corresponding to the value of the accepted coin, to be applied to the credit accumulator; and that coil also will immediately enable the coin-directing element to return to its normal, coin-intercepting position. Because that coil enables that coin-directing element to return to its normal, coin-intercepting position immediately, that coin-directing element will keep a coin, to which a thread or thin wire is attached, from being pulled back into register with the unit that tests coins; and yet that coin cannot effect the dispensing of merchandise or the application of a credit to the accumulator unless it is pulled back into register with that unit and then allowed to pass through that unit and into the coil which serves as a switch. It is, therefore, an object of the present invention to provide a coin-handling device which uses a coil as a switch, which interposes a coin-directing element between that coil and the unit which tests the coins, and by requiring a signal from the unit that tests the coins plus a signal from that coil before any merchandise can be dispensed or any credits can be applied to the credit accumulator.

Where desired, two or more coin-testing units can be arranged in tandem in advance of the coin-directing element; and each of those coin-testing units can respond to a coin of different denomination. Also, where desired, all of those coin-testing units can cause the coin-directing element to shift from its normal, coin-intercepting position to a position where it permits coins to move past it. In addition, if desired, the coil which acts as a switch can be made large enough and can be arranged so all accepted coins, regardless of their denominations, will pass through it. In such event, that coil can make certain that merchandise is dispensed or credits are applied to the credit accumulator only when a coin reaches and passes into that coil. Also, in such event, that coil can make certain that the coin-directing element returns to its normal coin-intercepting position immediately after a coin enters that coil.

By using "and" gates or similar electrical mechanisms, a number of testing units can be used with a single coil to properly apply different credit values to the credit accumulator. For example, by using "and" gates, four testing units can be used with a single coil to test German five-pfennig, ten-pfennig, fifty-pfennig, and one-mark coins and to apply appropriate credit values to the credit accumulator. The testing unit for the five-pfennig coin will be connected to one input terminal of an "and" gate, the testing unit for the ten-pfennig coin will be connected to one input terminal of a second "and" gate, the testing unit for the fifty-pfennig coin will be connected to one input terminal of a third "and" gate, and the testing unit for the mark coin will be connected to one input terminal of a fourth "and" gate. The coil, which acts as a switch, will be connected to second terminals of all four of the "and" gates; and, whenever any of those "and" gates receives a signal from a testing unit and from the coil, it will apply an appropriate credit to the credit accumulator.

The coin-handling device provided by the present invention has a coin entrance; and the four German coins can be introduced into that entrance in random fashion. A diameter-sizing gauge will cause the two smaller-diameter coins to pass to one coin passageway, and will cause the two larger-diameter coins to pass to a second coin passageway. The testing devices for the two smaller diameter coins will be arranged in tandem relation adjacent the one coin passageway, and the testing devices for the two larger-diameter coins will be arranged in tandem relation adjacent the second coin passageway. Where this is done, only two tests are needed to separate authentic coins of different denominations from each other and from spurious coins or coins of undesired denominations. This is desirable because it minimizes the time required to test and separate coins.

As each coin passes into the coil which acts as a switch, that coil will cause the coin-directing element to immediately return to its normal, coin-intercepting position. This is desirable because it will keep a second coin, which is introduced into the coin entrance immediately after a first coin has been so introduced, from reaching the coil. If that second coin were to be permitted to reach that coil, the patron who inserted that second coin would "lose" the value of that second coin; because the credit corresponding to a second coin cannot be applied to the credit accumulator unless the first coin enters the coil before that second coin reaches its testing unit. Coins pass through the coin-handling device of the present invention so rapidly that it would take a considerable effort and a high degree of skill to cause a second coin to reach its testing unit before the immediately-preceding coin had passed its testing unit and had entered the coil. However, even if a second coin could so reach its testing unit, the coin-directing element would reject that second coin and return it to the patron who inserted it.

The coin-directing element provided by the present invention should effectively block any withdrawing move-

ment of a thread or thin wire attached to an accepted coin; and hence should prevent any withdrawing movement of that coin. However, even if that coin-directing element permitted the thread or thin wire attached to a coin to move at all, that thread or thin wire could not move that coin back past that coin-directing element and into register with the testing unit. The most the movement of the coin, by the thread or thin wire, could accomplish would be to cause the coil to develop a signal; but that signal would not effect the dispensing of any merchandise or the applying of any credits to the credit accumulator, because a signal must be provided by the testing unit as well as by the coil. In this way, the present invention keeps patrons from using threads or thin wires to manipulate coins and cheat the coin-handling device of that invention.

Other and further objects and advantages of the present invention should become apparent from an examination of the drawing and accompanying description.

In the drawing and accompanying description a preferred embodiment of the present invention is shown and described but it is to be understood that the drawing and accompanying description are for the purpose of illustration only and do not limit the invention and that the invention will be defined by the appended claims.

In the drawing:

FIG. 1 is a conceptual showing of one preferred embodiment of coin-handling device that is made in accordance with the principles and teachings of the present invention,

FIG. 2 is a diagram of one circuit utilizing that coin-handling device,

FIG. 3 is a diagrammatic showing, partially in section, of the coin-handling device of FIG. 1, with the principles and teachings of the present invention,

FIG. 4 is a diagrammatic showing, in side elevation, of the coin-handling device of FIG. 1,

FIG. 5 is similar to the upper part of FIG. 3, but it shows a small-diameter coin about to fall into the passage for small-diameter coins,

FIG. 6 is similar to FIG. 5, but it shows a large-diameter coin being guided toward the passageway for large-diameter coins,

FIG. 7 is similar to the lower part of FIG. 3, but it shows a coin being intercepted by the coin-directing element,

FIG. 8 is similar to FIG. 7, but it shows the coin-directing element in position to permit a coin to pass by it,

FIG. 9 is similar to FIG. 3, but it shows a cash box below the coin-handling device, and

FIG. 10 is similar to the lower part of FIG. 9, but it emphasizes the coil which moves the coin-directing element.

Referring to the drawing in detail, the coin entrance for one preferred embodiment of coin-handling device that is provided by the present invention is denoted by the numeral 1; and that coin entrance is dimensioned so German five-pfennig, ten-pfennig, fifty-pfennig, and one-mark coins can readily pass through it and enter a coin passageway that is generally denoted by the numeral 2. That passageway is defined by walls 30 and 31 which are shown particularly by FIGS. 3, 5, 6 and 9. A generally-rectangular opening 32 is formed in the wall 31; and the lower edge of that opening is defined by a portion 34 of that wall which is bent inwardly and then downwardly. A coin-guiding wall 40 coacts with the inwardly and downwardly wall portion 34 to form a second passageway. A plate 36 abuts the wall 31, below the level of that plate serves as a runway for coins. A coin-guiding wall 38 is spaced from the runway 36 to define a third passageway. Coils 24 and 25 are disposed below the level of the coin-guiding wall 38; and the openings at the centers of those coils are vertically aligned with each

other and with the outlet of the coin passageway defined by runway 36 and the coin-guiding wall 38. Coils 26 and 27 are disposed below the level of the coin-guiding wall 40; and the openings at the centers of those coils are vertically aligned with each other and with the outlet of the coin passageway defined by the wall portion 34 and the coin-guiding wall 40.

A funnel-like member 7 underlies the vertically-aligned centers of the coils 24 and 25, and also underlies the vertically-aligned centers of the coils 26 and 27. That member will receive coins passing through the coils 24 and 25, and also will receive coins passing through the coils 26 and 27; and it will guide those coins toward the coin-intercepting portion 8a of a coin-directing element 8. The upper end of that coin-directing element is supported by a pivot 8c, and that coin-directing element is mounted adjacent a coil 8b. A spring 42 urges the coin-intercepting portion 8a of the coin-directing element 8 into position to block movement of coins from the funnel-like member 7 toward a coil 9 which acts as an electronic switch; but that spring will respond to energization of the coil 8b to move the coin-intercepting portion 8a of the coin-directing element 8 out of the path of such coins.

Coins which are permitted to pass to the coil 9 will pass through the center of that coil and cause that coil to develop a signal. Those coins will then move through a passageway 10 into a cash box 11. Coins that are prevented, by the coin-intercepting portion 8a of the coin-directing element 8, from passing to the coil 9 will be directed through a rejected coin passageway 12 to a returned coin receptacle 44 which is located at the exterior of the coin-handling device.

As shown by FIG. 3, the coin entrance 1 is inclined to the vertical, and hence any coins introduced through that coin entrance will be inclined to the vertical. The wall 30 has the same inclination as the coin entrance 1; and it will force coins, introduced through that coin entrance, to tend to rest upon the wall 31, with the lower edges of those coins supported by the runway 36. The diameters of German five-pfennig and fifty-pfennig coins are less than the distance between the runway 36 and the upper edge of the opening 32; and hence those coins will fall through that opening and be guided downwardly by the wall portion 34 and the coin-guiding wall 40 to the vertically-aligned openings in the coils 26 and 27. The diameters of German ten-pfennig and one-mark coins are greater than the distance between the runway 36 and the upper edge of the opening 32, and hence those coins will roll past the end of that runway and be guided downwardly to the vertically-aligned openings in the coils 24 and 25.

The showing of the coils 24-27 is diagrammatic only; and the passages through the coils 24 and 25 must be dimensioned so the largest coin which is intended to pass through the coin entrance 1 can easily fall through those passages. The coils 26 and 27 are dimensioned so the coins which fall through the opening 32 can easily pass through the passages in those coils. It will be noted that the coils 26 and 27 are mounted in tandem along the path for the German five-pfennig and fifty-pfennig coins; and this is desirable because it enables both of those coins to be tested in the same passageway. Similarly, it will be noted that the coils 24 and 25 are mounted in tandem along the path for the German ten-pfennig and one-mark coins, thereby enabling both of those coins to be tested in the same passageway.

When a German ten-pfennig or one-mark coin is introduced through the coin entrance 1, it will be too large to fall through the opening 32; and hence it will roll along the runway 36 and fall downwardly through the vertically-aligned passages in the coils 24 and 25. A German five-pfennig or fifty-pfennig coin introduced through the coin entrance 1 will fall through the opening 32, and then pass downwardly through the vertically-aligned passages

in the coils 26 and 27. Any coin passing through the coils 24 and 25 will strike the left-hand portion of the funnel-like member 7, as that member is viewed in FIG. 3, and it will be guided toward the coin-intercepting portion 8a of the coin-directing element 8. Any coin passing through the coils 26 and 27 will strike the right-hand portion of the funnel-like member 7, and it will be guided toward the coin-intercepting portion 8a of the coin-directing element 8. If that coin-intercepting portion is in the normal, coin-intercepting position shown by FIGS. 3, 7, 9 and 10, that coin will be kept from passing to the coil 9. Instead, that coin will roll down the rejected coin passageway 12 into the returned coin receptacle 44.

The coil 24 is part of an electronic coin tester 3 shown in FIG. 1; and that electronic coin tester preferably is like the electronic coin tester disclosed in our German patent application Ser. No. D46,446IXc/43b for Elektronisches Münzprüfverfahren für Metallische Münzen which was filed Feb. 5, 1965, or is like the electronic coin tester disclosed in Wolfgang Niehaus German patent application Ser. No. K56,207IXc/43b for Elektronisches Münzprüfverfahren für Metallische Münzen which was filed May 25, 1965 and June 11, 1965. Metal coins have specific resonant frequencies; and those resonant frequencies are dependent upon the dimensions of the coins, the materials or alloys of which the coins are made, and any plating on the surfaces of those coins. A coin which has been rendered resonant can coact with a coil, which is tuned to the resonant frequency of that coin, to develop a signal as that coin passes through that coil; and that signal can cause an electromagnetically-operated coin-deflecting element to move out of coin-rejecting position so that coin can be accepted. If desired, a single coil such as the coil 24 can transmit energy to coins passing through it to render those coins resonant; and then that coil can receive energy from any of those coins which is resonating at a frequency close to the resonant frequency of that coil to develop a signal which will effect the acceptance of that coin, but will not respond to any of those coins which is resonating at a materially-different frequency to develop such a signal—and hence such a coin will be rejected. On the other hand, if desired, a first coil can transmit energy to coins passing through it to render those coins resonant; and then a second coil such as the coil 24 can receive energy from any of those coins which is resonating at a frequency close to the resonant frequency of that second coil to develop a signal which will effect the acceptance of that coin, but will not respond to any of those coins which is resonating at a materially-different frequency to develop such a signal—and hence such a coin will be rejected. The coil 24 will coact with the rest of the electronic coin tester 3 to provide a usable signal whenever an authentic German ten-pfennig coin passes downwardly through that coil; but it will not coact with the rest of that electronic coin tester to provide a usable signal if any coin other than an authentic German ten-pfennig coin passes downwardly through that coil, because such other coin will not resonate at the resonant frequency of the coil 24. The coil 25 is part of an electronic coin tester 5, shown in FIG. 1; and that electronic coin tester preferably is like one of the electronic coin testers disclosed in said German patent applications. The coil 25 will be formed and dimensioned to resonate at the resonant frequency of an authentic German one-mark coin, and that coil will coact with the rest of that electronic coin tester to provide a usable signal whenever an authentic German one-mark coin passes downwardly through that coil; but it will not coact with the rest of that electronic coin tester to provide a usable signal if any coin other than an authentic German one-mark coin passes downwardly through that coil, because such other coin will not resonate at the resonant frequency of the coil 25. The coil 26 is part of an electronic coin tester 4, shown in FIG. 1; and that electronic coin tester preferably is

like one of the electronic coin testers disclosed in said German patent applications. The coil 26 will be formed and dimensioned to resonate at the resonant frequency of an authentic German five-pfennig coin, and that coil will coat with the rest of that electronic coin tester to provide a usable signal whenever an authentic German five-pfennig coin passes downwardly through that coil; but it will not coat with the rest of that electronic coin tester to provide a usable signal if any coin other than an authentic German five-pfennig coin passes downwardly through that coil, because such other coin will not resonate at the resonant frequency of the coil 26. The coil 27 is part of an electronic coin tester 6, shown in FIG. 1; and that electronic coin tester preferably is like one of the electronic coin testers disclosed in said German patent applications. The coil 27 will be formed and dimensioned to resonate at the resonant frequency of an authentic German fifty-pfennig coin, and that coil will coat with the rest of that electronic coin tester to provide a usable signal whenever an authentic German fifty-pfennig coin passes downwardly through that coil; but it will not coat with the rest of that electronic coin tester to provide a usable signal if any coin other than an authentic German fifty-pfennig coin passes downwardly through that coil, because such other coin will not resonate at the resonant frequency of the coil 27.

As indicated particularly by FIG. 2, the electronic coin tester 3 is connected to the "set" terminal of a bi-stable element 50 by a junction 52, the electronic coin tester 4 is connected to the "set" terminal of a bi-stable element 54 by a junction 56, the electronic coin tester 5 is connected to the "set" terminal of a bi-stable element 58 by a junction 60, and the electronic coin tester 6 is connected to the "set" terminal of a bi-stable element 62 by a junction 65. The electronic coin tester 3 is connected to the "re-set" terminals of the bi-stable elements 54, 58 and 62 by the junction 52 and by a junction 66 and a diode 68, and a junction 70 and diodes 72 and 74. The electronic coin tester 4 is connected to the "re-set" terminals of the bi-stable elements 50, 58 and 62 by the junction 56 and by a diode 76, a junction 78 and diodes 80 and 82. The electronic coin tester 5 is connected to the "re-set" terminals of the bi-stable elements 50, 54 and 62 by the junction 60 and by a junction 84 and diodes 86 and 88, and a diode 90. The electronic coin tester 6 is connected to the "re-set" terminals of the bi-stable elements 50, 54 and 58 by the junction 65 and by a junction 92 and a diode 94, and a junction 96 and diodes 98 and 100. The output of the bi-stable element 50 is connected to the upper input terminal of an "and" gate 17 by a junction 102, and is connected to the coil 8b by that junction, a diode 13, and junctions 106, 108 and 110. The output of the bi-stable element 54 is connected to the upper input terminal of an "and" gate 18 by a junction 112, and is connected to the coil 8b by that junction, a diode 14 and junctions 106, 108 and 110. The output of the bi-stable element 58 is connected to the upper input terminal of an "and" gate 19 by a junction 116, and is connected to the coil 8b by that junction, a diode 15, and junctions 108 and 110. The output of the bi-stable element 62 is connected to the upper input terminal of an "and" gate 20 by a junction 120, and is connected to the coil 8b by that junction, a diode 16 and junction 110. The coil 9, which acts as an electronic switch, is connected to the "re-set" terminals of the bi-stable elements 50, 54, 58 and 62 by a junction 124, a junction 126 and a diode 128, a junction 130 and diode 132, a junction 134 and diodes 136 and 138. The coil 9 also is connected to the lower input terminals of the "and" gates 17, 18, 19 and 20 by the junction 124 and by junctions 140, 142 and 144. The output terminals of the "and" gates 17, 18, 19 and 20 are connected to the input terminals of a credit accumulator 21, and the output of that credit accumulator can be connected to a merchandise dispenser by a conductor 22. The diodes 13,

14, 15, 16, 68, 72, 74, 76, 80, 82, 86, 88, 90, 94, 98, 100, 128, 132, 136 and 138 are used to prevent undesired interaction between the various portions of the circuit of FIG. 2.

5 When an authentic German five-pfennig coin is introduced into the coin entrance 1, it will fall downwardly through the opening 32 and pass through the coil 26. That coil will cause the electronic coin tester 4, of which it is a part, to apply a signal to the "set" terminal of the bi-stable element 54 via junction 56 and to apply a signal to the "re-set" terminals of the bi-stable elements 50, 58 and 62 via junctions 56 and 78 and diodes 76, 80 and 82. The diodes 63, 72 and 74 will keep a signal from being applied to the "set" terminal of the bi-stable element 50, the diodes 86, 88 and 90 will keep a signal from being applied to the "set" terminal of the bi-stable element 58, and the diodes 94, 98 and 100 will keep a signal from being applied to the "set" terminal of the bi-stable element 62. The bi-stable element 54 will immediately apply a negative signal to the upper input terminal of the "and" gate 18 via junction 112 and to the coil 8b via junction 112, diode 14, and junctions 106, 108 and 110; and that bi-stable element will continue to apply that negative signal to that upper input terminal and to the coil 8b. The diode 13 will keep that negative signal from being applied to the upper input terminal of the "and" gate 17, the diode 15 will keep that negative signal from being applied to the upper input terminal of the "and" gate 19, and the diode 16 will keep that negative signal from being applied to the upper input terminal of the "and" gate 20. The coil 8b will promptly rotate the coin-directing element 8 from the position shown by FIGS. 3, 7, 9 and 10 to the position shown by FIG. 8; and hence, when the five-pfennig coin then passes downwardly through the coil 27, enters the funnel-like member 7, and is directed toward the opening in the coil 9, that coin will not be intercepted by the coin-intercepting portion 8a of the coin-directing element 8. Instead, that coin will pass through the coil 9; and, thereupon, that coil will apply a negative signal to the lower input terminals of the "and" gates 17, 18, 19, and 20 via junctions 124, 140, 142 and 144, and also will apply that negative signal to the "re-set" terminals of each of the bi-stable elements 50, 54, 58 and 62 via junctions 124, 126, 130 and 134 and diode 138, via junctions 124, 126, 130 and 134 and diode 136, via junctions 124, 126 and 130 and diode 132, and via junctions 124 and 126 and diode 128, respectively. The diodes 68, 72 and 74 will keep that negative signal from being applied to the "set" terminal of the bi-stable element 50, the diodes 76, 80 and 82 will keep that negative signal from being applied to the "set" terminal of the bi-stable element 54, the diodes 86, 88 and 90 will keep that negative signal from being applied to the "set" terminal of the bi-stable element 58, and the diodes 94, 98 and 100 will keep that negative signal from being applied to the "set" terminal of the bi-stable element 62.

Because the "and" gates 17, 19 and 20 do not have negative signals applied to the upper input terminals thereof, those "and" gates will not be able to supply a negative signal to the credit accumulator 21. Because the bi-stable elements 50, 58 and 62 had not previously been "set," the application of negative signals to the "re-set" terminals of those bi-stable elements will not affect the condition of those bi-stable elements.

65 The overall result is that the signal provided by the coil 9 will cause the "and" gate 18 to apply a credit-accumulating signal to the credit accumulator 21, and will cause the bi-stable element 54 to re-set itself.

70 The five-pfennig coin must pass through the coil 27, as it moves from the coil 26 to the funnel-like member 7. However, the coil 27, and the electronic coin tester 6 of which it is a part, will not provide a signal that can "set" the bi-stable element 62, because that coil will not resonate at the resonant frequency of a five-pfennig coin.

Consequently, the five-pfennig coin will cause only the bi-stable element 54 to be "set."

When an authentic German ten-pfennig coin is introduced into the coin entrance 1, that coin will be too large to fall through the opening 32. Instead, that coin will roll along the runway 36 and then fall downwardly through the coil 24. That coil will cause the electronic coin tester 3, of which it is a part, to apply a signal to the "set" terminal of the bi-stable element 50 via junction 52 and to apply a signal to the "re-set" terminals of the bi-stable elements 54, 58 and 62 via junctions 52, 66 and 70 and diodes 68, 72 and 74. The diodes 76, 80 and 82 will keep a signal from being applied to the "set" terminal of the bi-stable element 54, the diodes 86, 88 and 90 will keep a signal from being applied to the "set" terminal of the bi-stable element 58, and the diodes 94, 98 and 100 will keep a signal from being applied to the "set" terminal of the bi-stable element 62. The bi-stable element 50 will immediately apply a signal to the upper input terminal of the "and" gate 17 via junction 102 and to the coil 8b via junction 102, diode 13, and junctions 106, 108 and 110; and that bi-stable element will continue to apply that negative signal to that upper input terminal and to the coil 8b. The diode 14 will keep that negative signal from being applied to the upper input terminal of the "and" gate 18, the diode 15 will keep that negative signal from being applied to the upper input terminal of the "and" gate 19, and the diode 16 will keep that negative signal from being applied to the upper input terminal of the "and" gate 20. The coil 8b will promptly rotate the coin-directing element 8 from the position shown by FIGS. 3, 7, 9 and 10 to the position shown by FIG. 8; and hence, when the ten-pfennig coin then passes downwardly through the coil 25, enters the funnel-like member 7, and is directed toward the opening in the coil 9, that coin will not be intercepted by the coin-intercepting portion 8a of the coin-directing element 8. Instead, the coin will pass through the coil 9; and, thereupon, that coil will apply a negative signal to the lower input terminals of the "and" gates 17, 18, 19 and 20 via junctions 124, 140, 142 and 144 and also will apply that negative signal to the "re-set" terminals of the bi-stable elements 50, 54, 58 and 62 via junctions 124, 126, 130 and 134 and diode 138, via junctions 124, 126, 130 and 134 and diode 136, via junctions 124, 126 and 130 and diode 132, and via junctions 124 and 126 and diode 128, respectively. The diodes 68, 72 and 74 will keep that negative signal from being applied to the "set" terminal of the bi-stable element 50, the diodes 76, 80 and 82 will keep that negative signal from being applied to the "set" terminal of the bi-stable element 54, the diodes 86, 88 and 90 will keep that negative signal from being applied to the "set" terminal of the bi-stable element 58, and the diodes 94, 98 and 100 will keep that negative signal from being applied to the "set" terminal of the bi-stable element 62. Because the "and" gates 18, 19 and 20 do not have negative signals applied to the upper input terminals thereof, those "and" gates will not be able to supply a negative signal to the credit accumulator 21. Because the bi-stable elements 54, 58 and 62 had not previously been "set," the application of negative signals to the "re-set" terminals of those bi-stable elements will not affect the condition of those bi-stable elements. The overall result is that the signal provided by the coil 9 will cause the "and" gate 17 to apply a credit-accumulating signal to the credit accumulator 21, and will cause the bi-stable element 50 to re-set.

The ten-pfennig coin must pass through the coil 25, as it moves from the coil 24 to the funnel-like member 7. However, the coil 25, and the electronic coin tester 5, of which it is a part, will not provide a signal that can "set" the bi-stable element 58, because that coil will not resonate at the resonant frequency of a ten-pfennig coin. Consequently, the ten-pfennig coin will cause only the bi-stable element 50 to be "set."

When an authentic German fifty-pfennig is introduced into the coin entrance 1, it will fall downwardly through the opening 32 and pass through the coil 26 and then through the coil 27. The coil 26, and the electronic coin tester 4, of which it is a part, will not provide a signal that can "set" the bi-stable element 54, because that coil will not resonate at the resonant frequency of a fifty-pfennig coin; but the coil 27 will cause the electronic coin tester 6, of which it is a part, to apply a signal to the "set" terminal of the bi-stable element 62 via junction 65 and to apply a signal to the "re-set" terminals of the bi-stable elements 50, 54 and 58 via junctions 65, 92 and 96 and diodes 100, 98 and 94. The diodes 68, 72 and 74 will keep a signal from being applied to the "set" terminal of the bi-stable element 59, the diodes 76, 80 and 82 will keep a signal from being applied to the "set" terminal of the bi-stable element 54, and the diodes 86, 88 and 90 will keep a signal from being applied to the "set" terminal of the bi-stable element 58. The bi-stable element 62 will immediately apply a signal to the upper input terminal of the "and" gate 20 via junction 120 and to the coil 8b via junction 120, diode 16, and junction 110; and that bi-stable element will continue to apply that negative signal to that upper input terminal and to the coil 8b. The diode 13 will keep that negative signal from being applied to the upper input terminal of the "and" gate 17, the diode 14 will keep that negative signal from being applied to the upper input terminal of the "and" gate 18, and the diode 15 will keep that negative signal from being applied to the upper input terminal of the "and" gate 19. The coil 8b will promptly rotate the coin-directing element 8 from the position shown by FIGS. 3, 7, 9 and 10 to the position shown by FIG. 8; and hence, when the fifty-pfennig coin then enters the funnel-like member 7, and is directed toward the opening in the coil 9, that coin will not be intercepted by the coin-intercepting portion 8a of the coin-directing element 8. Instead, that coin will pass through the coil 9; and, thereupon, that coil will apply a negative signal to the lower input terminals of the "and" gates 17, 18, 19 and 20 via junctions 124, 140, 142 and 144, and also will apply that negative signal to the "re-set" terminals of each of the bi-stable elements 50, 54, 58 and 62 via junctions 124, 126, 130 and 134 and diode 138, via junctions 124, 126, 130 and 134 and diode 136, via junctions 124, 126 and 130 and diode 132, and via junctions 124 and 126 and diode 128, respectively. The diodes 68, 72 and 74 will keep that negative signal from being applied to the "set" terminal of the bi-stable element 50, the diodes 76, 80 and 82 will keep that negative signal from being applied to the "set" terminal of the bi-stable element 54, the diodes 86, 88 and 90 will keep that negative signal from being applied to the "set" terminal of the bi-stable element 58, and the diodes 94, 98 and 100 will keep that negative signal from being applied to the "set" terminal of the bi-stable element 62. Because the "and" gates 17, 18 and 19 do not have negative signals applied to the upper input terminals thereof, those "and" gates will not be able to supply a negative signal to the credit accumulator 21. Because the bi-stable elements 50, 54 and 58 had not previously been "set," the application of negative signals to the "re-set" terminals of those bi-stable elements will not affect the condition of those bi-stable elements. The overall result is that the signal provided by the coil 9 will cause the "and" gate 20 to apply a credit-accumulating signal to the credit accumulator 21, and will cause the bi-stable element 62 to re-set itself.

When an authentic German mark is introduced into the coin entrance 1, that coin will be too large to fall through the opening 32. Instead, that coin will roll along the runway 36 and then fall downwardly through the coil 24, and the coil 25. The coil 24, and the electronic coin tester 3, of which it is a part, will not provide a signal that can "set" the bi-stable element 50 because that

coil will not resonate at the resonant frequency of a one-mark coin; but the coil 25 will cause the electronic coin tester 5, of which it is a part, to apply a signal to the "set" terminal of the bi-stable element 53 via junction 69 and to apply a signal to the "re-set" terminals of the bi-stable elements 50, 54 and 62 via junctions 60 and 84 and diodes 86, 88 and 90. The diodes 68, 72 and 74 will keep a signal from being applied to the "set" terminal of the bi-stable element 50, the diodes 76, 80 and 82 will keep a signal from being applied to the "set" terminal of the bi-stable element 54, and the diodes 94, 98 and 100 will keep a signal from being applied to the "set" terminal of the bi-stable element 62. The bi-stable element 53 will immediately apply a signal to the upper input terminal of the "and" gate 19 via junction 116 and to the coil 8b via junction 116, diode 15, and junctions 103 and 110; and that bi-stable element will continue to apply that negative signal to that upper input terminal and to the coil 8b. The diode 13 will keep that negative signal from being applied to the upper input terminal of the "and" gate 17, the diode 14 will keep that negative signal from being applied to the upper input terminal of the "and" gate 18, and the diode 16 will keep that negative signal from being applied to the upper input terminal of the "and" gate 20. The coil 8b will promptly rotate the coin-directing element 8 from the position shown by FIGS. 3, 7, 9 and 10 to the position shown by FIG. 8; and hence, when the one-mark coin enters the funnel-like member 7 and is directed toward the opening in the coil 9, that coin will not be intercepted by the coin-intercepting portion 8a of the coin-directing element 8. Instead, that coin will pass through the coil 9; and, thereupon, that coil will apply a negative signal to the lower input terminals of the "and" gates 17, 18, 19 and 20 via junctions 124, 149, 142 and 144, and also will apply that negative signal to the "re-set" terminals of each of the bi-stable elements 50, 54, 53 and 62 via junctions 124, 126, 130 and 134 and diode 138, via junctions 124, 126, 130 and 134 and diode 136, via junctions 124, 126, and 130 and diode 132, and via junctions 124 and 126 and diode 128, respectively. The diodes 63, 72 and 74 will keep that negative signal from being applied to the "set" terminal of the bi-stable element 50, the diodes 76, 80 and 82 will keep that negative signal from being applied to the "set" terminal of the bi-stable element 54, the diodes 86, 88 and 90 will keep that negative signal from being applied to the "set" terminal of the bi-stable element 53, and the diodes 94, 98 and 100 will keep that negative signal from being applied to the "set" terminal of the bi-stable element 62.

Because the "and" gates 17, 18 and 20 do not have negative signals applied to the upper input terminals thereof, those "and" gates will not be able to supply a negative signal to the credit accumulator 21. Because the bi-stable elements 50, 54 and 62 had not previously been "set," the application of negative signals to the "re-set" terminals of those bi-stable elements will not affect the condition of those bi-stable elements. The overall result is that the signal provided by the coil 9 will cause the "and" gate 19 to apply a credit-accumulating signal to the credit accumulator 21, and will cause the bi-stable element 53 to re-set itself.

Preferably, the bi-stable elements 50, 54, 53 and 62 are of the type which "set" immediately in response to the application of a signal to the "set" terminal thereof; and the "Conventional bistable multivibrator" in FIGURE 198 on page 203 of TM 11-690 Department of The Army Technical Manual entitled "Basic Theory And Application Of Transistors" which was published in March of 1959 is one such bi-stable element. Such bi-stable elements will promptly and unerringly respond to the signals from the electronic coin testers 3, 4, 5, and 6 to assume the required "set" positions. Each of the "and" gates 17, 18, 19 and 20 could be identical to the "and" gate shown in FIGURE 203A on page 213 of

the said Army Technical Manual. The signals from the coil 9 must actuate the appropriate "and" gates and must also re-set the appropriate bi-stable elements. It is important that the signal from the coil 9 be applied to the appropriate "and" gates before the corresponding bi-stable elements are re-set. If necessary, a delay element could be provided between junction 124 and the junction 126 to make certain that the appropriate bi-stable elements remain "set" until after the coil 9 has applied its signal to the corresponding "and" gates.

The use of the "and" gates 17, 18, 19 and 20 keeps a patron from improperly causing credit-accumulating signals to be applied to the credit accumulator 21, as by using a thread or thin wire to recurrently move a coin through the coil 9. The coin-directing element 8 is, of course, intended to keep a patron from using a thread or thin wire to move a coin relative to that coil; but even if a patron is, somehow, able to move such a coin, any signal from the coil 9 could not by itself, cause a credit-accumulating signal to be applied to the credit accumulator 21. Only the "and" gates 17, 18, 19 and 20 can supply credit-accumulating signals to the credit accumulator 21; and none of those "and" gates can respond solely to signals from the coil 9. Instead, each of those "and" gates requires a signal from a bi-stable element in addition to the signal from the coil 9.

It will be noted that the coil 9 cannot develop the signal which will be applied to the lower input terminals of the "and" gates 17, 18, 19 and 20 until the coin has moved a substantial distance through that coil; and, by that time, that coin is wholly below the coin-intercepting portion 8a of the coin-directing element 8. Furthermore, at the instant the coil 9 applies the signal to the lower input terminals of the "and" gates 17, 18, 19 and 20, that coil also applies the signal to the "re-set" terminals of the bi-stable elements 50, 54, 53 and 62. As a result, the appropriate bi-stable element will re-set itself, and permit the coin-directing element 8 to return to its normal, coin-intercepting position, before the patron can jerk the coin back up into position to block the returning movement of that coin-directing element. Consequently, it is not possible to affix a thread or thin wire to a coin and use that coin to cheat the coin-handling device provided by the present invention.

If a spurious coin or a coin of undesired denomination is introduced through the coin entrance 1, that coin will roll along the runway 36, if it is in the size range of a ten-pfennig or one-mark coin; and that coin will then fall downwardly through the coils 24 and 25. The electronic coin testers 3 and 5, of which those coils are parts, will not develop signals which can "set" the bi-stable elements 50 and 53 because those coils will not resonate at the resonant frequency of that coin. As a result, that spurious coin or coin of undesired denomination will be intercepted by the coin-intercepting portion 8a of the coin-directing element 8 and will be directed toward the rejected coin passageway 12. Similarly, if a spurious coin or coin of undesired denomination, in the size range of five-pfennig or fifty-pfennig coins is introduced, that coin will fall through the opening 32 in the wall 31 and pass downwardly through the coils 26 and 27. The electronic coin testers 4 and 6, of which those coils are parts, will not develop signals which can "set" the bi-stable elements 54 and 62 because those coils will not resonate at the resonant frequency of that coin. As a result, that spurious coin or coin of undesired denomination will be intercepted by the coin-intercepting portion 8a of the coin-directing element 8 and will be directed toward the rejected coin passageway 12.

The credit accumulator 21 will receive credit-accumulating signals and will accumulate the credits corresponding thereto. When the total of the accumulated credits equals the sales price, that credit accumulator will develop a signal; and that signal will pass through the conductor 22 to a suitable merchandise dispensing

machine. As that machine dispenses the desired merchandise, it will automatically re-set the credit accumulator 21.

If desired, a switch could be connected intermediate the electronic coin tester 3 and the junction 52, a second switch could be connected intermediate the electronic coin tester 4 and the junction 56, a third switch could be connected intermediate the electronic coin tester 5 and the junction 60, and a fourth switch could be connected intermediate the electronic coin tester 6 and the junction 65; and those switches could be controlled by the credit accumulator 21. Such an arrangement would prevent the acceptance of a coin whenever the value of the accumulated credits exceeded the difference between the value of that coin and the sales price. For example, if the sales price was one mark and sixty pfennig, and if the electronic coin tester 5, the bi-stable element 58 and the coil 9 responded to the introduction of a one mark coin to cause the "and" gate 19 to apply a one mark credit-accumulating signal to the credit accumulator 21, that credit accumulator would then open the switch between the electronic coin tester 5 and the junction 60. If a second one mark coin was then inserted in the coin entrance 1, that coin would pass through the coil 25; but the electronic coin tester 5 could not respond to that coin to "set" the bi-stable element 58; and hence the coin-intercepting portion 8a of the coin-directing element 8 would reject that coin and direct it to the rejected coin passageway 12. If a fifty pfennig coin was then inserted, the electronic coin tester 6, the bi-stable element 62, and the coil 9 would cause the "and" gate 20 to supply a fifty pfennig credit-accumulating signal to the credit accumulator 21. That credit accumulator would respond to the accumulated credits of one mark and fifty pfennigs to open the switch between the electronic coin tester 6 and the junction 65. As a result, any further fifty pfennig coin which was introduced through the coin entrance 1 and passed down through the coil 27 would be unable to cause the electronic coin tester 6 to "set" the bi-stable element 62. This means that the further fifty pfennig coin would be intercepted by the coin-intercepting portion 8a of the coin-directing element 8 and would be directed to the rejected coin passageway 12. If a five pfennig coin was then inserted through the coin entrance 1, the electronic coin tester 4, the bi-stable element 54, and the coil 9 would cause the "and" gate 18 to apply a five pfennig credit-accumulating signal to the credit accumulator 21. That credit accumulator would respond to the total accumulated credits of one mark and fifty-five pfennig to open the switch between the electronic coin tester 3 and the junction 52; and the opening of that switch would keep a ten pfennig coin from being accepted, as by keeping the electronic coin tester 3 from responding to such a coin to "set" the bi-stable element 50. This is desirable; because the acceptance of a ten pfennig coin would make the total value of the inserted coins greater than the sales price—with consequent loss to the patron.

If a five pfennig, rather than a ten pfennig, coin were introduced through the coin entrance 1, the electronic coin tester 4 would again "set" the bi-stable element 54, and the coil 9 would again coat with that bi-stable element and the "and" gate 18 to apply a five pfennig credit-accumulating signal to the credit accumulator 21. That credit accumulator would then respond to the total credits of one mark and sixty pfennig to apply a signal to the merchandise-dispensing machine via the conductor 22.

If a ten pfennig coin had been inserted instead of the first five pfennig coin, that ten pfennig coin would have caused the electronic coin tester 3 to "set" the bi-stable element 50, and the coil 9 would have coated with that bi-stable element and the "and" gate 17 to apply a ten pfennig credit-accumulating signal to the credit accumulator 21. That credit accumulator would then have responded to the total credits of one mark and sixty

pfennig to apply a signal to the merchandise-dispensing machine via the conductor 22.

The drawing and accompanying description have shown and described a coin-handling device which can test, and accumulate the values of, coins of four different denominations; but that coin-handling device can be made so it can test, and accumulate the values of, coins of fewer or greater numbers of denominations. Also, if desired, a change-dispensing system could be associated with the credit accumulator 21 to permit change to be dispensed in the event the total value of the inserted coins exceeded the sales price. In such event, the switches between the electronic coin testing devices 3, 4, 5 and 6 and the junctions 52, 56, 60 and 65, respectively, would be unnecessary.

Because the electronic coin testers 3, 4, 5 and 6 are capable of distinguishing between coins of generally similar diameters, because those electronic coin testers cause signals to be applied to "and" gates, and because the coil 9 also applies signals to those "and" gates, to cause them to supply credit-accumulating signals, the coin-handling device of the present invention does not need a separate coin-actuated switch for each denomination of coin. Further, that coin-handling device does not need a separate testing passageway for each coin of different denomination. Moreover, that coin-handling device needs just the one coin-directing element 8.

If a patron were to attach a thread or thin wire to a one-mark coin, he might be able to intercept and hold that coin after that coin had passed through the coil 25 and had caused the electronic coin testing device 5 to "set" the bi-stable element 58 but before that coin had reached the coin-directing element 8. That bi-stable element would apply a signal to, and would continue to maintain that signal at, the upper input terminal of the "and" gate 19. If that patron then inserted a lesser-value coin, in the expectation that the consequent signal from the coil 9 would cause the "and" gate to apply a one-mark credit-accumulating signal to the credit accumulator 21, that patron would be disappointed. Specifically, as the electronic coin tester for that lesser value coin "sets" its corresponding bi-stable element, that electronic coin tester would simultaneously "re-set" the bi-stable element 58 and the other two bi-stable elements. The re-setting of the bi-stable element 58 would remove the signal at the upper input terminal of the "and" gate 19; and the subsequent application to the lower input terminal of that "and" gate of the signal from the coil 9 could not cause that "and" gate to apply a credit-accumulating signal to the credit accumulator 21. As a result, the patron would receive credit for the insertion of the lesser-value coin and nothing more.

The action of each electronic coin tester 3, 4, 5 or 6 in re-setting all of the other bi-stable elements at the same time it sets its corresponding bi-stable element makes certain that only one bi-stable element is "set" at any given time. Consequently, if a patron tries to develop a signal at the upper input terminal of any of the "and" gates 17, 18, 19 and 20 with a tethered coin, and then tries to use a second coin to obtain credits exceeding the value of that second coin, that patron will be disappointed.

Whereas the drawing and accompanying description have shown and described a preferred embodiment of the present invention, it should be apparent to those skilled in the art that various changes can be made in the form of the invention without affecting the scope thereof.

What we claim is:

1. A coin-handling device that comprises: a coin tester that is disposed adjacent a path for coins and that is actuated by an authentic coin of a predetermined denomination in said path, a coin-responsive element that is disposed adjacent said path and that is actuated by a coin of said predetermined denomination in said path, said coin tester and said coin-responsive element being spaced apart along said path so an authentic coin of said pre-

determined denomination in said path will initially actuate said coin tester but is kept from actuating said coin-responsive element, and a control device that requires two signals to actuate it, said coin tester responding to the actuation thereof by a coin of said predetermined denomination in said path to cause one of said signals to be applied to said control device, said coin-responsive element responding to the actuation thereof by a coin of said predetermined denomination in said path to cause the other of said signals to be applied to said control device, said control device remaining unactuated if a coin of said predetermined denomination is permitted to actuate said coin tester but is kept from actuating said coin-responsive element, said control device remaining unactuated if a coin of said predetermined denomination is held adjacent said coin tester and is moved back and forth through said path to repeatedly actuate said coin tester, said control device remaining unactuated if a coin of said predetermined denomination is held adjacent said coin-responsive element and is moved back and forth through said path to repeatedly actuate said coin-responsive element unless said coin is caused to actuate said coin tester before each actuation of said coin-responsive element, the spacing apart of said coin tester and said coin-responsive element along said path making it difficult to move a coin of said predetermined denomination back and forth through a sufficient distance in said path to cause said coin to actuate both said coin tester and said coin-responsive element, and thereby effect actuation of said control device.

2. A coin-handling device that comprises: a coin tester that has a sensor disposed adjacent a path for coins, a second coin tester that has a second sensor disposed adjacent said path for coins, the first said sensor and said second sensor being spaced apart along said path, a control device, and a second control device, the first said coin tester responding to a coin of a predetermined denomination in said path to become actuated and thereby cause a signal to be applied to the first said control device, said second coin tester responding to a coin of a second predetermined denomination in said path to become actuated and thereby cause a signal to be applied to said second control device, the first said coin tester being substantially insensitive to coins of said second predetermined denomination, said second coin tester being substantially insensitive to coins of the first said predetermined denomination, the spacing apart of said sensors of said coin testers along said path substantially completely preventing interaction between said sensors.

3. A coin-handling device that comprises: a coin tester that is disposed adjacent a path for coins and that is actuated by an authentic coin of a predetermined denomination in said path, a coin-responsive element that is disposed adjacent said path and that is actuated by a coin of said predetermined denomination in said path, said coin tester and said coin-responsive element being spaced apart along said path so an authentic coin of said predetermined denomination in said path will initially actuate said coin tester and will thereafter actuate said coin-responsive element, and a control device that requires two signals to actuate it, said coin tester responding to the actuation thereof by a coin of said predetermined denomination in said path to cause one of said signals to be applied to said control device, said coin-responsive element responding to the actuation thereof by a coin of said predetermined denomination in said path to cause the other of said signals to be applied to said control device, said control device remaining unactuated if a coin of said predetermined denomination is permitted to actuate said coin tester but is kept from actuating said coin-responsive element, said control device remaining unactuated if a coin of said predetermined denomination is held adjacent said coin tester and is moved back and forth through said path to repeatedly actuate said coin tester, said control device remaining unactuated if a coin of said predetermined denomination

is held adjacent said coin-responsive element and is moved back and forth through said path to repeatedly actuate said coin-responsive element unless said coin is caused to actuate said coin tester before each actuation of said coin-responsive element, the spacing apart of said coin tester and said coin-responsive element along said path making it difficult to move a coin of said predetermined denomination back and forth through a sufficient distance in said path to cause said coin to actuate both said coin tester and said coin-responsive element, and thereby effect actuation of said control device, and a member interposed between said coin tester and said coin-responsive element to resist movement of a coin of said predetermined denomination from a position adjacent said coin-responsive element to a position adjacent said coin tester.

4. A coin-handling device that comprises: a coin tester that is disposed adjacent a path for coins and that is actuated by an authentic coin of a predetermined denomination in said path, a coin-responsive element that is disposed adjacent said path and that is actuated by a coin of said predetermined denomination in said path, said coin tester and said coin-responsive element being spaced apart along said path so an authentic coin of said predetermined denomination in said path will initially actuate said coin tester and will thereafter actuate said coin-responsive element, and a control device that requires two signals to actuate it, said coin tester responding to the actuation thereof by a coin of said predetermined denomination in said path to cause one of said signals to be applied to said control device, said coin-responsive element responding to the actuation thereof by a coin of said predetermined denomination in said path to cause the other of said signals to be applied to said control device, said control device remaining unactuated if a coin of said predetermined denomination is permitted to actuate said coin tester but is kept from actuating said coin-responsive element, said control device remaining unactuated if a coin of said predetermined denomination is held adjacent said coin tester and is moved back and forth through said path to repeatedly actuate said coin tester, said control device remaining unactuated if a coin of said predetermined denomination is held adjacent said coin-responsive element and is moved back and forth through said path to repeatedly actuate said coin-responsive element unless said coin is caused to actuate said coin tester before each actuation of said coin-responsive element, the spacing apart of said coin tester and said coin-responsive element along said path making it difficult to move a coin of said predetermined denomination back and forth through a sufficient distance in said path to cause said coin to actuate both said coin tester and said coin-responsive element, and thereby effect actuation of said coin device, and a member interposed between said coin tester and said coin-responsive element to resist movement of a coin of said predetermined denomination back and forth in said path adjacent said coin-responsive element.

60   5. A coin-handling device that comprises: a coin tester that is disposed adjacent a path for coins and that is actuated by an authentic coin of a predetermined denomination in said path, a coin-responsive element that is disposed adjacent said path and that is actuated by a coin of said predetermined denomination in said path, said coin tester and said coin-responsive element being spaced apart along said path so an authentic coin of said predetermined denomination in said path will initially actuate said coin tester and will thereafter actuate said coin-responsive element, and a control device that requires two signals to actuate it, said coin tester responding to the actuation thereof by a coin of said predetermined denomination in said path to cause one of said signals to be applied to said control device, said coin-responsive element responding to the actuation thereof by a coin of said predetermined denomination in said path to cause the other of said signals to be applied to said control device, said control device remaining unactuated if a coin of said

predetermined denomination is permitted to actuate said coin tester but is kept from actuating said coin-responsive element, said control device remaining unactuated if a coin of said predetermined denomination is held adjacent said coin tester and is moved back and forth through said path to repeatedly actuate said coin tester, said control device remaining unactuated if a coin of said predetermined denomination is held adjacent said coin-responsive element and is moved back and forth through said path to repeatedly actuate said coin-responsive element unless said coin is caused to actuate said coin tester before each actuation of said coin-responsive element, the spacing apart of said coin tester and said coin-responsive element along said path making it difficult to move a coin of said predetermined denomination back and forth through a sufficient distance in said path to cause said coin to actuate both said coin tester and said coin-responsive element, and thereby effect actuation of said control device, said coin-responsive element being spaced so far from said coin tester that a coin of said predetermined denomination must move wholly beyond said coin tester before it can move into position adjacent said coin-responsive element.

6. A coin-handling device that comprises: a coin tester that is disposed adjacent a path for coins and that is actuated by an authentic coin of a predetermined denomination in said path, a coin-responsive element that is disposed adjacent said path and that is actuated by a coin of said predetermined denomination in said path, said coin tester and said coin-responsive element being spaced apart along said path so an authentic coin of said predetermined denomination in said path will initially actuate said coin tester and will thereafter actuate said coin-responsive element, and a control device that requires two signals to actuate it, said coin tester responding to the actuation thereof by a coin of said predetermined denomination in said path to cause one of said signals to be applied to said control device, said coin-responsive element responding to the actuation thereof by a coin of said predetermined denomination in said path to cause the other of said signals to be applied to said control device, said control device remaining unactuated if a coin of said predetermined denomination is permitted to actuate said coin tester but is kept from actuating said coin-responsive element, said control device remaining unactuated if a coin of said predetermined denomination is held adjacent said coin tester and is moved back and forth through said path to repeatedly actuate said coin tester, said control device remaining unactuated if a coin of said predetermined denomination is held adjacent said coin-responsive element and is moved back and forth through said path to repeatedly actuate said coin-responsive element unless said coin is caused to actuate said coin tester before each actuation of said coin-responsive element, the spacing apart of said coin tester and said coin-responsive element along said path making it difficult to move a coin of said predetermined denomination back and forth through a sufficient distance in said path to cause said coin to actuate both said coin tester and said coin-responsive element, and thereby effect actuation of said control device, a rejected coin passageway that communicates with said path intermediate said coin tester and said coin-responsive element, and a coin-directing element that is disposed adjacent the point of communication of said rejected coin passageway with said path, said coin-directing element normally being disposed to direct coins toward said rejected coin passageway and thereby keep said coins from actuating said coin-responsive element, said coin-directing element responding to actuation of said coin tester to move out of its normal position and thereby permit a coin that has actuated said coin tester to pass to said coin-responsive element to actuate said coin-responsive element, said coin-directing element thereafter responding to actuation of said coin-responsive element to return to its normal position.

7. A coin-handling device that comprises: a coin tester that is disposed adjacent a path for coins and that is actuated by an authentic coin of a predetermined denomination in said path, a coin-responsive element that is disposed adjacent said path and that is actuated by a coin of said predetermined denomination in said path, said coin tester and said coin-responsive element being spaced apart along said path so an authentic coin of said predetermined denomination in said path will initially actuate said coin tester and will thereafter actuate said coin-responsive element, and a control device that requires two signals to actuate it, said coin tester responding to the actuation thereof by a coin of said predetermined denomination in said path to cause the other of said signals to be applied to said control device, said control device remaining unactuated if a coin of said predetermined denomination is permitted to actuate said coin tester but is kept from actuating said coin-responsive element, said control device remaining unactuated if a coin of said predetermined denomination is held adjacent said coin tester and is moved back and forth through said path to repeatedly actuate said coin-responsive element unless said coin is caused to actuate said coin tester before each actuation of said coin-responsive element, the spacing apart of said coin tester and said coin-responsive element along said path making it difficult to move a coin of said predetermined denomination back and forth through a sufficient distance in said path to cause said coin to actuate both said coin tester and said coin-responsive element, and thereby effect actuation of said control device, a rejected coin passageway that communicates with said path intermediate said coin tester and said coin-responsive element, and a coin-directing element that is disposed adjacent the point of communication of said rejected coin passageway with said path, said coin-directing element normally being disposed to direct coins toward said rejected coin passageway and thereby keep said coins from actuating said coin-responsive element, said coin-directing element responding to actuation of said coin tester to move out of its normal position and thereby permit a coin that has actuated said coin tester to pass to said coin-responsive element to actuate said coin-responsive element.

8. A coin-handling device that comprises: a coin tester that has a sensor disposed adjacent a path for coins, a second coin tester that has a second sensor disposed adjacent said path for coins, the first said sensor and said second sensor being spaced apart along said path, a control device, and a second control device, the first said coin tester responding to a coin of a predetermined denomination in said path to become actuated and thereby cause a signal to be applied to the first said control device, said second coin tester responding to a coin of a second predetermined denomination in said path to become actuated and thereby cause a signal to be applied to said second control device, the first said coin tester being substantially insensitive to coins of said second predetermined denomination, said second coin tester being substantially insensitive to coins of the first said predetermined denomination, the spacing apart of said sensors of said coin testers along said path substantially completely preventing interaction between said sensors, and a coin-responsive element that is disposed adjacent said path, the first said control device requiring a second signal in addition to said signal which the first said coin tester causes to be applied to said control device, said second control device requiring a second signal in addition to said signal which said second coin tester causes to be applied to said control device, and said coin-responsive element responding to a coin of either

sensors of said coin testers along said path substantially completely preventing interaction between said sensors, and a credit accumulator that receives credit-accumulating signals from said control devices, said credit accumulator having a sales price set therein, said credit accumulator acting whenever the credits accumulated thereby differ from said sales price by a value less than the value of a coin of said second predetermined denomination to disconnect said second coin tester from said second control device, whereby the total value of inserted coins cannot exceed said sales price.
